[57] CLAIM

The ornamental design for a wall-covering adhesive applicator, as shown and described.

DESCRIPTION

FIG. 1 is a front view of a wall-covering adhesive applicator showing one embodiment of our new design.

FIG. 2 is a top plan view thereof.

FIG. 3 is a rear view thereof.

FIG. 4 is a right-hand side view thereof.

FIG. 5 is a bottom plan view thereof.

FIG. 6 is a sectional view taken at line 6—6 in FIG. 5 and viewed in the direction of the arrows.

FIG. 7 is a front view showing a second embodiment of our design.

FIG. 8 is a rear view of the second embodiment.

FIG. 9 is a sectional view thereof taken at line 9—9 in FIG. 7 and viewed in the direction of the arrows.

FIG. 10 is a top plan view of the second embodiment.

FIG. 11 is a bottom view of the second embodiment. The appearance of the right side of the second embodiment is identical to that of the first embodiment as shown in FIG. 4.

The appearance of the left-hand side of both embodiments is a mirror image of the right-hand side shown in FIG. 4.
